UNITED STATES PATENT OFFICE.

AUGUST BOUCHERY, OF BROOKLYN, NEW YORK.

LOCK.

1,215,470.

Specification of Letters Patent. Patented Feb. 13, 1917.

Application filed February 24, 1916. Serial No. 80,132.

To all whom it may concern:

Be it known that I, AUGUST BOUCHERY, a citizen of the United States, residing in the borough of Brooklyn, in the county of 5 Kings, city and State of New York, have invented new and useful Improvements in Locks, of which the following is a specification.

This invention relates to locks in which a keeper fixed to a door frame or door is provided with a perforated ear or ears adapted to engage in recesses in one end of a lock casing fixed to a door or door frame, and with which perforated ears tongues connected to a bolt mounted in the casing to have sliding movement in a direction longitudinal of the keeper are adapted to coöperate, the said bolt being operable by a hand knob and also by a key, and it is the object 20 of the invention to improve the general construction of locks of this character and to provide improved means to actuate the bolt, and to simplify and cheapen the construction of such locks and at the same time increase the efficiency thereof.

In the drawing accompanying and forming a part of this specification Figure 1 is a side elevation, partly in section, of a lock showing an embodiment of my invention.

Fig. 2 is a cross sectional view showing the same applied to a door.

Fig. 3 is a perspective view of the bolt; and

Fig. 4 is a perspective view of a keeper to be used in connection with the lock.

Similar characters of reference designate like parts throughout the different views of the drawing.

The embodiment of the invention shown in the drawing consists of a casing 6 having a flanged portion 7 at the top and bottom and the rear end, the front end of the casing having a convexedly formed portion 8, as clearly shown in Fig. 2, thus providing 15 a casing open at one side which is closed by a removable bolt 9 secured to the casing 6 by screws 10 passing through perforations in said bolt and having screw threaded connection with lugs 11 in the casing with the 0 plate adjacent its edges abutting against the flanged portion 7 of the casing. The end portion 8 of the casing when secured to a door frame or door is adapted to extend be-

yond the edge thereof, as shown in Fig. 2, and has a recess or recesses 12 therein for the 55 engagement of a perforated ear or ears 13 of a keeper or catch plate 14.

A bolt 15 has a pair of laterally extending projections or arms slidably mounted on a pair of rods 17 fixed at their ends within the 60 casing to permit of the bolt having longitudinal movement relative to the keeper and prevent any lateral movement of the bolt. Tongues 19 are carried by projections 18 extending opposite from the bolt to the arms 65 16 to extend in a plane parallel with the bolt the said tongues preferably being circular in cross section to fit and slidably engage in the openings or perforations in the keeper ears 13.

To impart movement to the bolt to throw the bolt tongues into and out of engagement with the perforations of the keeper ears there is provided a cam member 20 fixed to a pintle 21 rotatably mounted in the lock 75 casing to engage between the projections 16 of the bolt. In Fig. 1 said cam is shown as

engaging with and in position to maintain the bolt tongues out of the perforations in the keeper ears, the cam being retained in 80 such position by a spring 22 fixed at one end to a pin 23 with the free end engaging with and in front of pins 25 projecting laterally from the cam. The pin 23 also serves as a stop to prevent the cam from being thrown 85

back too far and out of operative engagement with the upper bolt projections 16. The cam is actuated by a hand knob 24 which is preferably located on the inside of the door, and to cause the bolt tongues to engage in 90

the ear perforations the knob 24 is rotated to move the cam in the direction shown by the arrow in Fig. 1 causing the cam to engage with the lower projection 16, the pins 25 during this movement tensioning and 95 throwing the spring outward. When the cam is moved to a position directly opposite to that shown in Fig. 1 it will engage with the lower projection 16 and maintain the bolt in such position with the bolt tongues 100

in the ear perforations, and the cam retained in such position by the spring 20 engaging with the pins 25, a stop pin 26 preventing the cam from being thrown out of operative engagement with the lower projec- 105 tion 16. It will be obvious that with the

cam in this position the bolt tongues will be in locking position, and to throw them to unlocking position it is only necessary to rotate the knob 24 in a direction reverse to 5 the arrow.

The lock is preferably operable from the outer side of the door by a key, and for this purpose there is provided ordinary key operated mechanism comprising a tumbler carrying barrel 27 in which is rotatably mounted a barrel 28 having a slot for a key 29, and having openings 21 for the engagement of the tumblers to prevent the rotation thereof, the said tumblers being adapted to be thrown out of said openings to permit rotation of the barrel by the key, the barrel 28 having means fixed thereto, as shown at 30, to connect it to the cam whereby as said barrel is rotated by the key such movement 10 will be transmitted to the cam to throw the bolt to either locking or unlocking position.

Having thus described my invention I claim:

1. In a lock, the combination with a keeper having a perforated ear, of a lock casing having a recess in one end in which the keeper ear is adapted to engage; a bolt having a tongue extending parallel with the bolt located in the recessed portion of the lock 25 casing to engage in the ear perforation when in locking position, and having a pair of lateral extensions whereby the bolt is mounted in the casing to have to and fro sliding movement in line with the ear perforation 30 and prevent said bolt from having rotative and lateral movement; and an operating member rotatable in the casing to engage between said extensions and coöperating with one of said extensions to throw the bolt into 35 the perforation in the ear and maintain it therein, and to coöperate with the other extension to throw the bolt out of the ear 40 perforation and maintain it in such position.

2. In a lock, the combination with a keeper having perforated ears, of a lock casing having recesses in one end in which the keeper ears are adapted to engage; a bolt having a pair of lateral extensions and 45 tongues extending parallel with the bolt, said tongues being located in the recessed portion of the casing and adapted to engage in the ear perforations, and a pair of rods in the casing upon which the bolt extensions are slidably mounted to permit movement of 50 the bolt longitudinally of the keeper and prevent the bolt from having lateral and rotative movement, substantially as and for the purpose specified.

3. In a lock, the combination with a keeper having perforated ears, of a lock casing having a convexedly formed portion at one end with recesses therein and in which recesses the keeper ears are adapted to engage; a bolt having a pair of parallel lateral 60 extensions whereby it is mounted in the casing 65

to have to and fro movement longitudinal of the keeper and prevented from having lateral and rotative movement, said bolt having tongues extending parallel with the bolt located in the convexedly formed portion 70 of the casing and adapted to engage in the ear perforations when the bolt is in locking position; rotatable means to coöperate with said lateral extensions of the bolt to throw the bolt to cause the bolt tongues to engage 75 in the ear perforations and to throw them out of said ear perforations; and a spring to coöperate with said rotatable means to maintain said means in position with the bolt engaging in or thrown out of engagement with the ear perforations, substantially 80 as and for the purpose specified.

4. In a lock, the combination with a keeper having perforated ears, of a casing having a convexedly formed portion at one end with recesses therein in which the keeper ears are adapted to engage; a bolt having a pair of lateral extensions and tongues on the side opposite from said extensions extending parallel with the bolt located in the convexedly 90 formed portion of the casing and adapted to engage in the ear perforations of the keeper; guides in the casing upon which the lateral extensions of the bolt are slidably mounted to permit movement of the bolt in a direction longitudinally of the keeper and prevent said bolt from having lateral and rotative movement; rotatable means in the casing operable from the exterior thereof to coöperate with said lateral extensions of the 95 bolt to cause the bolt tongues to engage in the ear perforations of the keeper and maintain them therein, and to throw said tongues out of said ear perforations and a spring to coöperate with said rotatable means to 100 maintain said means in position with the bolt engaging in or thrown out of engagement with the ear perforations, substantially 105 as and for the purpose specified.

5. In a lock, the combination with a keeper having perforated ears, of a lock casing having recesses formed in one end in which the keeper ears are adapted to engage; a bolt having a pair of lateral extensions and a pair of tongues extending parallel with the bolt on the side opposite to the extensions, said tongues being located in the recessed portion of the casing and adapted to engage in the ear perforations of the keeper; a pair of rods in the casing upon which the lateral 115 extensions of the bolt are slidably mounted to permit said bolt to have movement longitudinally of the keeper only; and a cam rotatably mounted in the casing between said lateral extensions of the bolt operable 120 from the exterior of the casing and adapted to coöperate with one of said bolt extensions to throw the bolt tongues into and maintain them in the ear perforations of the keeper, and coöperate with the other bolt extension 125 130

to throw said bolt tongues out of the ear perforations of the keeper and maintain the bolt in such position.

6. In a lock, the combination with a keeper having perforated ears, of a lock casing having recesses formed in one end in which the keeper ears are adapted to engage; a bolt having a pair of lateral extensions and a pair of tongues extending parallel with the bolt 5 on the side opposite to the extensions, said tongues being located in the recessed portion of the casing and adapted to engage in the ear perforations of the keeper; a pair of 10 guide rods in the casing upon which the lateral extensions of the bolt are slidably mounted to permit movement of the bolt longitudinally of the keeper only; a cam ro-

tatably mounted in the casing between said bolt extensions operable from the exterior of the casing and adapted to coöperate with 20 one of said extensions to throw the bolt tongues into and maintain them in the ear perforations of the keeper and coöperate with the other bolt extension to throw said bolt tongues out of the ear perforations in 25 the keeper and maintain them in such position; and a spring to coöperate with the cam to maintain said cam in position to coöperate with the bolt extensions to maintain the bolt tongues in engagement with the ear 30 perforations of the keeper or out of engagement therewith.

AUGUST BOUCHERY.
